(57) **CLAIM**

The ornamental design for a micro tube array container, as shown and described.

DESCRIPTION

FIG. 1 is a perspective view of the micro tube array container of the invention;

FIG. 2 is a front view of the micro tube array container depicted in FIG. 1, with the rear view being identical;

FIG. 3 is a left side view of the micro tube array container depicted in FIG. 1, with the right side view being identical;

FIG. 4 is a top view of the micro tube array container depicted in FIG. 1;

FIG. 5 is a bottom view of the micro tube array container depicted in FIG. 1;

FIG. 6 is a sectional view of the micro tube array container depicted in FIG. 1, taken along line 6-6 in FIG. 4; and,

FIG. 7 is a perspective view of the micro tube array container depicted in FIG. 1, with sample tubes being shown in dashed lines as reflecting the environment of use and not forming part of the design.
